United States Patent Office.

EDGAR F. EATON, OF NORTHFORD, CONNECTICUT.

Letters Patent No. 95,332, dated September 28, 1869; antedated September 17, 1869.

IMPROVED BUCKLE.

The Schedule referred to in these Letters Patent and making part of the same.

To all whom it may concern:

Be it known that I, EDGAR F. EATON, of Northford, in the county of New Haven, and State of Connecticut, have invented a new Improvement in Buckles; and I do hereby declare the following, when taken in connection with the accompanying drawings, and the letters of reference marked thereon, to be a full, clear, and exact description of the same, and which said drawings constitute part of this specification, and represent, in—

Figure 1, a front view.

Figure 2, a rear view of the buckle complete.

Figures 3, 4, and 5, the three parts detached.

This invention relates to an improvement in what are known as three-part buckles, that is to say, the frame, loop, and tongues; and

The invention consists in forming the two tongues in one piece, the loop in a second piece, and hinging the frame to both the tongue and loop by bending the two ends of the frame between the tongues and around both the base of the tongue and one side of the loop, so that both are hinged to the frame, and move independent, the one of the other.

In order to the clear understanding of my invention, I will fully describe the same, as illustrated in the accompanying drawings.

A is the frame, seen enlarged in fig. 3, formed from any suitable metal, its two ends curved inward, so that from out to out they are the same distance as between the two tongues *a a*, the said two tongues

a a being formed from a single piece of wire bent at right angles to their base *b*, the space between the two tongues corresponding to the distance from out to out of the two ends of the frame.

B, the loop, seen enlarged in fig. 4, is formed from a single piece of metal, the two ends soldered together or covered by a metal tube, as seen in fig. 4, to support the two ends.

The whole side of the loop is curved at *d* to prevent lateral movement of the loop when hinged to the frame.

The whole side of the loop and base of the tongue are placed together, then the two ends of the frame are clasped over the base of the tongue and the whole side of the loop, so as to allow a free and independent movement of all the parts.

Thus formed, the two tongues pass over the ends of the frame and rest upon the body of the frame, as seen in fig. 1.

I do not broadly claim a buckle formed in three parts so that each may be moved independent of the other parts, as such, I am aware, is not new; but

What I do claim, and desire to secure by Letters Patent, is—

The frame A, loop B, and tongues *a a*, all constructed and united, as herein set forth.

EDGAR F. EATON.
